Specification of Letters Patent. Patented Oct. 31, 1911.

Application filed August 13, 1910. Serial No. 577,091.

To all whom it may concern:

Be it known that we, WILLIAM P. QUENTELL, a citizen of the United States, residing in the city, county, and State of New York, and FRANKLIN JUDGE, a citizen of the United States, residing at Norwalk, in the county of Fairfield and State of Connecticut, have invented certain new and useful Improvements in Calculating-Machines, of which the following is a specification.

This invention relates to calculating machines for performing operations in addition, subtraction, etc., and has reference more particularly to calculating machines of the type disclosed in Patent Number 966,410, dated Aug. 2, 1910.

The present invention includes numerous improvements upon the machine of the patent above referred to, these improvements being directed particularly to decreasing the cost of production of the machine, increasing the strength and wearing qualities of the machine, rendering the operation of the machine more reliable and making the machine more convenient to use and less liable to get out of order.

One feature of the present invention which is of great importance resides in the provision of a multiple-unit construction whereby practically all of the mechanism for use in calculating in one numerical order may be constructed and assembled complete, separate from and independent of the mechanisms for calculating in the other numerical orders, and subsequently the desired number of these completed units may be mounted side by side within the casing of the machine and used together. In machines such as calculating machines employing a great number of parts, many of which are small, it is well known that the cost of assembling the parts is an important item in the total cost of producing the machine. We have found that by employing the multiple-unit construction above referred to in a calculating machine, whereby practically all of the mechanism for calculating in a single numerical order may be assembled complete upon a single support and handled as a unit, the cost of assembling the parts for a complete machine is greatly reduced, and furthermore, that with this construction great strength and good wearing qualities may be obtained;

moreover, when such a multiple-unit construction is employed, the cost of making any repairs which may become necessary during the period of use of the machine is very materially reduced, for with this construction the several units may be taken out as a whole and only that one which requires repair need be disassembled. In addition to this feature of the machine, the invention includes various other features of novelty, all of which will be hereinafter pointed out in detail.

The preferred embodiment of the invention is illustrated in the accompanying drawings in which—

Figure 1 is a top view of the machine broken away and sectioned in part, Figs. 2 and 3 are longitudinal sections on lines 2 and 3, 3 respectively of Fig. 1, Fig. 4 is an elevation of one of the units, Fig. 5 is a top view of the same, Fig. 6 is a section on line 6, 6, of Fig. 4, Fig. 7 is a top view of the pivoted slide bar, Fig. 8 is a transverse section through the carrying mechanism, Fig. 9 is a view of the rear portion of the unit shown in Fig. 4 with certain of the parts removed, Figs. 10 and 11 are detail views of the operating mechanism showing two positions thereof, Fig. 12 is a view of the mechanism shown in Figs. 10 and 11 from the opposite side thereof, Fig. 13 is a top view of the frame of the machine showing the operating handle and certain of the parts actuated thereby, Fig. 14 is a detail view of the operating handle and certain of the parts actuated thereby, Fig. 15 is a sectional elevation of one of the number-wheels, Fig. 16 is a sectional view on the line 16, 16, of Fig. 15 and Fig. 17 is an elevation of one of the number-wheels showing the side thereof opposite that shown in Fig. 15.

The calculating machine shown in the drawings is of the character known as a "key-set" machine wherein the depression of keys positions certain of the operating parts of the machine in accordance with the value of the keys depressed and thereafter an operating device may be moved manually or in any other suitable manner to cause the number-wheels of the machine to be actuated an amount depending upon the extent of movement of the parts positioned by the

depression of the keys. A plurality of rows of keys are provided, as many rows as the number of numerical orders in which it is desired to operate, each row comprising 5 nine keys numbered from one to nine. One key in each row may be depressed for each operation, and when that key is depressed, it is locked in its depressed position and the other keys in the row are locked against depression. When a key in a row is depressed, it permits a slide-bar corresponding to that row to move in the direction of its length a distance corresponding to the value of the key depressed, and as this slide-bar moves 10 thus, it carries a pawl around upon a gear wheel with which that pawl coacts, the movement of the pawl thus being commensurate with the movement of the slide-bar. Upon actuation of the operating device, all 15 the pawls which have been moved thus are turned to their initial positions, moving their gear wheels with them, and the gear wheels cause corresponding rotation of the number wheels, which either indicate the result of 20 the operation or are positioned for printing the result upon a suitable paper strip. In combination with these parts a carrying mechanism is employed whereby any one of the mechanisms can cause the mechanism of 25 the next higher order to advance one unit as will be well understood.

In accordance with the present invention, a multiple-unit construction is employed; with this construction each row of keys, the 30 slide-bar coacting therewith, the number-wheel actuated on the return of that slide-bar to its initial position and the carrying mechanism corresponding to that number-wheel are all mounted upon a single support 35 so that all of these parts for one numerical order may be assembled upon that support and thereafter a suitable number of these units may be placed together in a machine. The preferred form of support 40 is a strip of sheet-metal of suitable configuration and this support may have one or more integral portions thereof bent at an angle to the body portion of the support and of the requisite length to serve as 45 spacers for separating the several supports the required distance. Fig. 1 shows a machine made up of eight such units, this machine being adapted for operation in dollars and cents up to one million dollars. The 50 construction of each of the units employed in the machine is best illustrated in Figs. 4 to 7. Referring to these figures, it will be seen that the supporting member for the unit consists of a piece of sheet-metal 1, 55 having its forward end 2 turned at a right angle to the body portion of the strip to form a spacer, as will be hereinafter described. A row of nine keys 3 is mounted upon the support 1, these keys being numbered from one to nine beginning at the

front of the machine. Each of these keys 3 is mounted upon a stem 4 and is adapted to slide vertically upon the support 1; for this purpose each key-stem 4 is provided with two slots through which extend the shanks of studs 5 entering openings in the support 1. Each key is normally held in a raised position by means of a spring 6 one end of which is secured to an eye 7 formed upon the key-stem 4 and the other end of which is secured to one of the studs 5. At its lower end each key is provided with a downwardly extending projection 8 and in rear of this a laterally extending projection 9. Also each key is provided with a laterally extending pin or stud 10. The lower ends of all of the keys in the row are adapted to coact with a pivoted sliding-bar 11 of angular cross-section. This bar is pivotally mounted in openings formed one in the laterally extending end 2 of the support 1 and the other in a similar lateral projection 12 integral with support 1. In the body-portion of the bar 11 are a plurality of spaced openings or slots of progressively increasing length, as shown in Fig. 7, through which the projections 8 on the key-stems are adapted to project when the keys are depressed.

The bar 11 as above stated is of angular cross-section, it being bent lengthwise to form a side-wall 13 and at the top thereof a flange 14 directed toward the key-stems. In the bottom wall of the bar 11 is an opening and the upwardly turned end of a link 15 enters loosely into this opening. A spring 16 is connected at one end to the link 15 and at the other end to the lateral extension 2 of the support 1 so that this spring tends to draw the link 15 and the slide-bar 11 forwardly. A spring 17 is connected at one end to the link 15 and at the other to an eye formed upon the slide-bar 11 so that this spring tends to turn the slide-bar 11 on its pivots far enough to carry the end of the wall 13 of the slide-bar opposite the end of a stud 18 mounted upon the extension 2 of the support 1. When the bar 11 is in this position, as shown in Fig. 6, it is held against movement actuated by spring 16. When any key 3 is depressed the extension 8 thereon is projected through its corresponding opening 19 in the slide-bar 11 and thereafter the lateral projection 9 on the key-stem engages the slide-bar 11 and rocks that bar on its pivots sufficient to carry the end of the side-wall 13 free of the stud 18; when this occurs the spring 16 draws the link 15 and slide-bar 11 forwardly until further movement of the slide-bar is arrested by the projection 8 on the stem of the key which has been depressed engaging the rear wall of the slot 19 in bar 11 through which it has been projected. When the slide-bar 11 is rocked on its pivots in the

manner thus described by means of the lateral projection 9, the lateral projection 10 on the key-stem has been carried by the downward movement of the key below the flange 14 on the slide-bar and the pivotal movement of the slide-bar carries the flange 14 over the pin or projection 10 on the key which has been depressed so that flange 14 will preclude that key from being returned to its initial position by its spring 6; also this movement of the slide-bar will carry the flange 14 under the pins or studs 10 on the stems of all of the other keys in the row so that it will preclude any one of these other keys from being depressed until the slide-bar has been returned to its initial position, as shown in Fig. 6.

Mounted upon the side of the supporting member 1 opposite that upon which the keys 3 are mounted is a strip which may be operated when desired to hold in its depressed position any key which has been depressed through a plurality of operations of the machine, this mechanism being provided for use in multiplying. This strip 20 (Figs. 3 and 5) is pivotally mounted upon the support 1 by means of parallel links 21 which are pivoted at one end to the strip 20 and at the other end to the support 1. The strip 20 is provided with a plurality of lateral projections 22, one for each key 3, and these projections extend through inclined slots provided in the support 1 as shown in Fig. 4. For coaction with the projections 22 each key-stem 4 is provided with a projection 23, the upper edge of which is inclined. It will be seen that if any key is depressed and thereafter the strip 20 is moved forwardly of the machine, the projection 22 on the strip 20 corresponding to the key depressed will be moved over the inclined upper edge of the projection 23 on the key depressed and will serve to hold that key in its depressed position until the strip 20 is returned to its initial position. Each strip 20 is provided with an upwardly extending portion 24 at its forward end for coaction with the device for operating all of the strips 20 simultaneously.

It will be seen from Fig. 7 that the slide-bar is provided with seven openings, these being graduated in length. The stem of the "1" key is shown at 30 in Fig. 7 and it will be seen that its downwardly projecting end 8 lies opposite the end of the body-portion of the slide-bar 11 so that it will coact with this end to arrest the sliding movement of the bar 11 at the proper point. The "9" key is not provided with a downwardly extending portion 8; this key when depressed merely rocks the slide-bar so as to carry it out of coaction with the end of the stud 18 and the stud is made of such length that the slide-bar will have the movement appropriate for the "9" key when

the end of the slide-bar 11 moves from coaction with the end of the stud 18 into coaction with the laterally projecting end 2 of the supporting-member 1.

Secured to the supporting-member is a stud 25 on which is pivotally mounted a gear-wheel 26; this gear-wheel is adapted to be operated by a pawl 27 carried by a pawl-carrying arm 41 which is also pivotally mounted upon the stud 25. The forward end of the link 15 is pivotally connected to the pawl-carrying arm 41 so that when the link 15 moves forwardly with the slide-bar 11 actuated by spring 16 it will draw the pawl-carrying arm 41 and the pawl 27 around about the stud 25 as an axis, the teeth of the pawl 27 riding over the teeth of the gear 26 without actuating that gear. When the pawl-carrying arm is returned to its initial position, in which it is shown in Fig. 4, the tooth of the pawl 27 catches in the teeth of the gear 26 and rotates the gear a distance corresponding to the distance which the pawl is moved and therefore corresponding to the distance which the slide-bar is moved. In addition to the stud 25 forming a pivot for the gear 26, studs 28 and 29 are mounted upon the support 1 and adapted to support certain of the parts of the carrying mechanism. All of these studs together with the integral projection 12 on the support 1 may be accurately formed as to their length so that they will serve as spacers for spacing apart the several units employed in a single machine.

In assembling the parts for a machine, as many units constructed as above described as are required for a machine of the desired capacity are placed side by side and these are held in proper relative position by threading bars 31 and 32 through openings provided in the supporting members 1 of the several units. The units will be held at the proper distance apart by means of the spacers, consisting of the integral lateral projections 2 and 12 on the supports 1 and the studs 25, 28 and 29.

At the right hand side of the machine, as shown in Fig. 1, a dummy-supporting member 33 is provided to act as a spacer between the first unit and the side-plate of the machine. The laterally turned end 2 of this support 33 bears against the side-frame 34 of the machine and the support 33 may be provided with a stud corresponding to the studs 28 on the supports 1 which also bears against the side-frame 34. A sheet-metal piece 38 may be placed between the support 33 and the side-frame 34 at the rear of the machine, this being provided with integral inwardly turned projections, as shown in Fig. 13, which bear against support 33 and which facilitate securing a cover-plate in position. At the left hand

side of the machine another dummy-support 35 is provided and suitable spacers 36 are positioned between this support 35 and the side-plate 37 of the machine. A plate 38 is also provided at this side of the machine. A plurality of tie-bars 39 are then positioned extending between the two side-frames 34 and 37 and screws are turned into the ends of these tie-bars so as to draw the side-frames tightly together and cause them to hold the several units of the machine firmly between them. One of these tie-bars 40 may be so positioned that it will serve as a support for the several links 15 to prevent the latter from moving vertically downward.

The mechanism for operating the number wheels will now be described. As above stated each unit is provided with a gear-wheel 26 operated by a pawl mounted on a pawl-carrying arm 41 pivotally mounted on stud 25 and having the link 15 pivotally connected thereto. The pawl 27 is not pivotally mounted directly upon the arm 41 but instead is pivotally mounted upon a lever 42 which is pivotally mounted at 43 upon the pawl-carrying arm 41. The pivotal connection between pawl 27 and the lever 42 passes through a slot 44 provided in the arm 41. Pivotally mounted upon the pawl-carrying arm is a trigger 45 having a lateral projection 46 which is adapted to engage a shoulder formed on the lever 42 so as to hold the lever and the pawl 27 carried thereby against movement about the pivot 43 of the lever except when it is necessary to carry over. A spring 47 is connected at one end to the trigger 45 and at the other end to the pivotal connection between the pawl 27 and lever 42. This spring serves two purposes, it tends to hold the trigger down upon the end of lever 42 and in coaction with the shoulder of that lever, and it tends to turn the lever 42 backwardly on its pivot to such a position that the trigger 45 can co-act with the shoulder on the lever. The pawl-carrying arm 41 is provided with an opening 48 through which extends a stud 49 carried by the pawl 27. Pivotally mounted upon the pivot-pin connecting the link 15 with the pawl-carrying arm 41 is a locking lever 50. A spring 51 is connected at one end to this lever and at the other end to the stud 49 and serves the double purpose of holding the pawl 27 yieldingly in coaction with the teeth of gear 26 and of holding the lever 50 yieldingly in the position in which it is shown in Figs. 9 and 12. When lever 50 is in this position, one end 52 thereof is directly in rear of the inner end of the lever 42 and serves to preclude movement of lever 42 in case trigger 45 is accidentally displaced. The opposite end 53 of lever 50 extends adjacent to the edge of the pawl-carrying arm 41 and

when lever 50 is in locking position this end 53 projects beyond the edge of the arm 41 as shown in Figs. 9 and 12. Lever 50 is also provided with a lateral projection 55 entering a slot in the pawl-carrying arm 41 to limit the movement of lever 50. The movement of the operating arm 41 in one direction is limited by a stud 54 projecting from the support 1, this stud serving to prevent overthrow of the operating arm as the result of momentum.

When a key is depressed, resulting in the forward movement of the slide-bar 11, the link 15 and the pawl carrying arm together with the parts moved thereby are carried around the pivot of wheel 26 in accordance with the movement of link 15. A handle is then operated to return the pawl-carrying arm and the parts carried thereby to their initial position and when these parts are moved thus, they turn wheel 26 a distance corresponding to the value of the key depressed. If it is necessary to carry one to the wheel thus actuated, the trigger 45 is released and the lever 42 is caused to turn about its pivot 43 so as to carry pawl 27 forward and thus move wheel 26 one step farther, the lever 50 being rocked to unlock lever 42 and permit this movement of the latter. The lever 42 is provided with a lateral projection 56 at its rear end adapted to be engaged by the inner end of a lever 57 pivotally mounted upon the stud 28 and pressed by a spring 58 to turn it in a counter-clockwise direction as seen in Figs. 10 and 9. In a completed unit the levers 57 are not under tension, the springs 58 merely bearing upon studs 59 on the levers 57 for convenience in assembling. When the units for a machine are assembled, however, a bail 60 is employed as hereinafter described and the ends of the springs 58 are carried over this bail 60 as shown in Figs. 2, 10 and 11, so as to exert a tension upon levers 57. Each time a pawl carrying arm is moved from the Fig. 11 position to the Fig. 10 position, the laterally turned end of the lever 42 engages the inner end of the lever 57 and raises that lever slightly against the tension of spring 58 so that if the trigger 45 co-acting with that lever 42 is moved to release the lever 42, spring-actuated lever 57 will rock lever 42 on its pivot and cause it to move pawl 27 and wheel 26 to effect the carrying over.

The mechanism for releasing the triggers 45 at the proper times together with the indicating mechanism of the machine, will now be described.

For convenience in resetting the number wheels at the zero position all of the number wheels of the machine are mounted upon a shaft extending across the machine. The number wheels are therefore not placed upon a unit when assembling the latter but in-

stead all of the number wheels are positioned when assembling the several units for a machine. Thus it will be seen that no number wheel is shown in Figs. 4 and 5 which are views of the unit whereas in Figs. 2 and 10 which are views of a completed machine the number wheel is shown at 61, this being secured to a pinion 62 meshing with the corresponding gear 26. Each number wheel 61 also has secured thereto a cam 63. Pivotedly mounted upon each supporting member 1 is a cam lever 64 having a projection adapted to ride upon the periphery of the cam 63, this lever bearing down upon the cam 63 by means of a spring 65 connected at one end to the lever 64 and at the other end to the projection 12. When the number wheel passes from the "9" to the "0" position the cam-lever drops over the tooth on the cam 63. The stud 29 on the support 1 forms a pivot for two levers 66 and 67 each of which is provided with a spring 68 connected at one end to the lever and at the opposite end to a stud 69 on the support 1, so that these springs tend to turn the levers in a clockwise direction as seen in Figs. 2, 4, 9, 10 and 11. Lever 67 at its lower end has a bell-crank lever 70 pivotally mounted thereon and a spring 71 (Fig. 9) connects a pin on this lever with a pin on lever 67 so as to hold the lever 70 in the position in which it is shown in Fig. 9 and in which position its end may be engaged by the end of the cam lever 64 when the latter drops over the tooth of the cam 63 as is plainly indicated in Fig. 10. When the cam lever does so drop it engages lever 70 and by turning the latter causes it to turn lever 67 in a counter-clockwise direction. Lever 67 at its upper end is provided with a lateral projection 72 (Fig. 8) which in the completed machine projects on one side of the upper end of the lever 66 of the next adjacent unit so that when lever 67 is thus actuated by its lever 64 it causes the lever 66 of the next adjacent unit to turn in a counter-clockwise direction on its pivot 29. Each lever 66 at its lower end is provided with a lateral projection 73. With this projection 50 coacts a latch 74 pivotally mounted upon the stud 75 formed on the support 1. This latch is actuated by a spring 76 so that when lever 66 is moved from the Fig. 2 position to the Fig. 10 position by the lever 67 of the next lower unit, the latch 74 will be moved into coaction with the projection 73 of the lever 66 and hold lever 66 in the position to which it is moved against the tension of its spring 68. When lever 66 is in this position, its lateral projection 73 is in position to contact with the beveled end of the trigger 45 so that when the operating arm is moved second, this beveled end of the trigger will engage projection 73 as indicated in Fig. 10 and the trigger will be raised against the

tension of its spring 47 so as to release the lever 42 and allow that lever and the pawl 27 pivoted thereto to make the extra movement necessary for carrying over.

The operating handle 77 of the machine 76 is pivotally mounted upon a stud projecting laterally from the dummy plate 33 and the head of this handle is enlarged and provided with a segmental gear 78. At the opposite side of the machine a stud is provided on the plate 35 forming a pivot for a sector 79 which is provided with a segmental gear similar to the gear 78. These two gears mesh with pinions 80 carried by a shaft 81, the ends of which are received in bearings 80 in the side-plates of the machine. Extending between the handle 77 and the sector 79 is an operating rod 82 which is adapted to engage the operating arms 41 so as to turn them to their initial positions after they have been moved around by the depression of the keys. On account of the unit construction adopted in the machine it would be very objectionable to have the parts 77 and 79 mounted upon a shaft extending across the machine and when no such shaft is employed the rod 82 would be subjected to a twisting strain if means were not provided to guard against this. The segmental gears on the parts 77 and 79 meshing with pinions mounted on the same shaft serve the purpose of relieving the rod 82 of such twisting strains. The parts 77 and 79 are provided with corresponding cam grooves 83 adapted to receive studs on levers 84 pivotally mounted upon studs 85 upon the plates 33 and 35. At their opposite ends these levers 84 carry the bail 60 above referred to. This bail extends over the ends of the levers 57 and also over projection 105 upon the latches 74 and it extends under the ends of the springs 58 which actuate the levers 57. By turning the handle 77 in a counter-clockwise direction as seen in Fig. 14, the operating rod 82 will be carried into engagement with the edge of each of the operating arms 41 so as to move those arms and the parts carried thereby from the positions to which they had been moved by the depression of keys back to their initial 115 positions. Before moving the arms 41, however, the rod 82 engages the ends 53 of the levers 50 and rocks those levers sufficiently to cause them to unlock the levers 42. During this movement of the operating handle the bail 60 will be rocked by the grooves 83 so as to raise bail 60 from the ends of the levers 57 and latches 74. When the operating handle is returned to its initial position, the operating rod 82 is retracted 125 and the cams 83 lower the bail 60. When bail 60 is lowered thus, it engages the end of each latch 74 which has been actuated by its spring 76 to engage a lever 36 and the bail turns the latch 74 against the tension 130

6
of its spring 76 sufficient to cause the latch to release the lever 66 and allow the latter to be returned to its initial position by its spring 68. When bail 60 is lowered, it also engages the ends of the levers 57 and depresses those ends sufficient to raise the opposite ends of the levers 57 and thus relieve the tension exerted by levers 57 upon the carrying levers 42. Thus at the end of 10 the return movement of the handle, such of the levers 42 as have been actuated to carry from one order to the next higher order, may be immediately returned to their initial positions by means of their springs 15 47 and locked in this position by their triggers 45.

The construction preferred for the number wheels 61 is shown in Figs. 15, 16 and 17. As here shown a sleeve 86 is provided 20 upon which the pinion 62 is formed and the number wheel 61 is secured to this sleeve by means of a plurality of projections 87 passing through the openings in the wheel 61 and having their ends turned over to 25 serve as rivets. The cam 63 is fitted upon the sleeve 86 and a rivet 88 passes through the cam and one of the projections 87 on sleeve 86. This rivet 88 serves as a pivot pin for a detent 89, the end of which is 30 adapted to pass through an opening in the sleeve 86, and, when resetting the number wheels, to enter a notch in the shaft 90 on which the number wheels are mounted. In 35 assembling the parts for a machine the shaft 90 is inserted through openings provided in the supports 1, and after its end is passed through each of the supports, a number wheel for that unit is properly positioned and the shaft 90 is passed through the 40 wheel 86 of that number wheel. When the shaft 90 is in the normal position, the detents 89 actuated by springs 91 bear upon smooth portions of the shaft, but the shaft 90 may be moved in the direction of its 45 length to bring slots therein under the detents 89, so that the detents for the several number wheels may enter these notches when shaft 90 is rotated; then by rotating shaft 90 the several wheels will automatically 50 become clutched to the shaft and all of the wheels will be rotated to the zero position. The notches in shaft 90 in which the detents 89 are received are inclined at one end so that when the number wheels 55 have been brought to the zero position, the shaft 90 may be moved lengthwise back to its initial position and the detents 89 will again bear on smooth portions of shaft 90 so that the several wheels will be unclutched 60 from the shaft and may be rotated free thereof by means of gears 26.

In order to prevent the gears 26 and the number wheels driven thereby from being accidentally displaced, a detent bail is provided for coaction with the teeth of the sev-

eral gears 26. This bail is shown at 92 and is pivotally mounted (Fig. 2) upon the plates 33 and 35 (Fig. 1). At its ends the bail is provided with projections 93 (Fig. 14) adapted to coact with cams 94 secured 70 upon shaft 81. When the projections 93 are in the notches of the cams 94 as shown in Fig. 14, the bail 92 is in engagement with the teeth of the gears 26 and holds those gears and the number wheels against movement. When the shaft 81 is rotated by the movement of the operating handle, the cams 94 will act upon the projections 93 to move the bail 92 from engagement with the gears 26. While resetting the number wheels it is 80 necessary that the gears 26 rotate freely and therefore the bail 92 must be disengaged from the gears 26. For this purpose a construction similar to that shown in the patent above referred to is employed; the shaft 90 85 has a sleeve 95 secured thereto and provided with a conical surface which, when shaft 90 is moved lengthwise to the resetting position, engages the edge of the operating handle 77 (Fig. 14) and moves the operating handle sufficient to cause slight rotation of shaft 81, such as will cause disengagement of bail 92 and gears 26. Also it is necessary that while the shaft 90 is in the resetting position the handle 77 be held 90 against movement since such movement of the handle might result in breakage of the parts. For this purpose handle 77 is provided with a curved surface 96 which coacts with the curved surface of the sleeve 95 to 95 lock handle 77 against movement when shaft 90 has been moved lengthwise to the resetting position.

Springs 97 are connected at one end to the side-plates of the machine and at their opposite ends to the parts 77 and 79 connected by the operating rod 82 so that after handle 77 has been moved in one direction manually, these springs will return it to its initial position. Means are also provided for enforcing a full movement of the operating handle 77 in either direction before it can be moved in the opposite direction. This means consists of teeth 98 on the operating handle 77 and a lever 99 pivotally mounted 105 upon the side-frame of the machine in position to coact with these teeth. A spring 100 is connected to the lever 99 and adapted to hold it in the position in which it is shown 110 in Fig. 14. When handle 77 is moved to the left in that figure, teeth 98 engage the end of lever 99 and rock that lever slightly against the tension of spring 100, the lever riding over the teeth 98. When the movement of the lever 77 is completed the end of the 115 lever 99 enters an enlarged depression 101 in the lever 77 but if it be attempted to return lever 77 before its movement is completed, the end of lever 99 will engage the teeth 98 and prevent such return movement. 120 125 130

After the end of lever 99 has entered the depression 101, it can turn on its pivot through a substantial arc and during the return movement of the handle 77 the opposite side of the end of lever 99 rides on the teeth 98 and in the same manner enforces a complete return movement of the handle 77.

The mechanism for operating the strips 20 when it is desired to multiply, is shown in Figs. 1 to 4. A shaft 102 is pivotally mounted in the side frames of the machine and one end projects beyond the side frame 37 and is provided with a handle 103. On this shaft are cranks 104 connected by links 105 to a rod 106 which extends across the machine in rear of the projections 24 on the strips 20. These parts are held in the position in which they are shown by a spring 107 coiled upon shaft 102. By depressing handle 103, rod 106 is moved to the left in Fig. 3 and carries with it all of the strips 20 against the tension of small springs 107, each connected at one end to a strip 20 and at the other end to a stud on the support 1, and when the strips 20 are so moved they will hold down any keys which have been depressed during a plurality of operations of handle 77, as above described.

Loosely pivoted upon each stud 25 is a lever 108 having a segment of gear teeth 109 formed thereon concentric with stub 25 and these teeth are engaged by the teeth of a rack 110 formed on an error key 111. The stem of this key and the member 1 adjacent to the key are provided with slots to receive studs, one on the support and one on the key stem to guide the error key in its vertical movement. A spring 112 is secured at one end to the error key and at the opposite end to a support on the stud 1 to normally hold the error key in its raised position. When the key is depressed the lever 108 is turned about stud 25 by the gearing above described until its end engages the stud 49 on the pawl 27 and the beveled end of lever 108 acts on this stud to raise pawl 27 out of engagement with gear 26. The continued movement of the error key and lever 108 pushes the operating arm 41 and the pawl and other parts carried thereby back to their initial position and it will be seen that this is done without actuating the gear 26 and the number wheel with which it meshes.

The operation of the machine as thus constructed has been set forth in connection with the foregoing description. This construction possesses many advantageous features. The arrangement of the mechanism for each numerical order, as a unit, permitting the construction of these units in practically complete form and the assemblage of such number of units as is desired in a complete machine, results in a substantial economy in the manufacture of the machine and greatly reduces the cost of

making any repairs which may become necessary. In connection with this unit construction, the provision of gearing between the parts carrying the operating rod 82, such as the shaft 81 and the pinion 80 thereon, is of importance as it is essential that the operating rod 82 be relieved of twisting strains and that the two ends thereof should move in unison. It will be seen that in this machine the pawls for actuating the gear wheels are carried by the same arms which carry the bell-crank levers and the triggers therefor which are used in carrying over from one numerical order to the next higher one. With this construction a number of advantages are obtained; the machine is simplified by a reduction of the number of parts, the slide-bars are not actuated during the carrying over operation and the slots in the slide-bars may be made shorter, thus reducing the length of the machine or increasing the strength of the slide-bars. In connection with this mechanism it is of importance that the tension of the levers 57 upon the bell-crank levers 42 be relieved at the end of the stroke of the operating handle, so that the bell-crank levers employed in carrying over may become reset immediately upon the conclusion of the stroke of the operating handle. As soon as the bell-crank levers are thus reset, they are locked in position and held against accidental release by means of the locking-lever 50 which is actuated by its spring to resume its locking position and which is not unlocked until the operating rod is again brought into engagement therewith by a movement of the operating handle. The mechanism operated by the error key for restoring the pawl-carrying arm 105 possesses the advantage over that shown in the patent before referred to, that it permits of a better alinement of the parts constituting the mechanism for one numerical order, this alinement bringing each row of keys, its error key and its number wheel more closely in line.

Having described our invention, what we claim as new therein and desire to secure by Letters Patent of the United States is:

1. A calculating machine for calculating in a plurality of numerical orders comprising a plurality of individual units each having mechanism for calculating in one numerical order and carrying mechanism, and means for securing said units together, substantially as set forth.
2. A calculating machine for calculating in a plurality of numerical orders comprising a plurality of individual units each having mechanism for calculating in one numerical order and carrying mechanism including a laterally projecting member, and means for securing said units together side by side with the laterally projecting mem- 125 130 135

ber of the carrying mechanism of each unit in position to engage the mechanism of the next adjacent unit, substantially as set forth.

3. A calculating machine for calculating in a plurality of numerical orders comprising a plurality of individual units each having mechanism for calculating in one numerical order and carrying mechanism, means for securing said units together, and 10 an operating device common to all of said units, substantially as set forth.

4. A calculating machine for calculating in a plurality of numerical orders comprising a plurality of individual units each consisting of a supporting member and mechanism for calculating in one numerical order and carrying mechanism mounted thereon, and means for securing said units together, substantially as set forth.

26 5. A calculating machine for calculating in a plurality of numerical orders comprising a plurality of individual units each consisting of a supporting member and mechanism for calculating in one numerical order 25 and carrying mechanism mounted thereon, rods passing through openings in said supporting members to aline said units, spacing devices for spacing said units apart, and means for securing the units together, 30 substantially as set forth.

6. A calculating machine for calculating in a plurality of numerical orders comprising a plurality of individual units each having mechanism for calculating in one numerical order and carrying mechanism, spacing devices for spacing said units apart predetermined amounts, and means for securing the units together, substantially as set forth.

49 7. A calculating machine for calculating in a plurality of numerical orders comprising a plurality of individual units each having mechanism for calculating in one numerical order and carrying mechanism, means for securing said units together, an operating device common to all of said units and extending transversely with respect to them, and means for moving said device, substantially as set forth.

50 8. A calculating machine for calculating in a plurality of numerical orders comprising a plurality of individual units each having mechanism for calculating in one numerical order and carrying mechanism, 55 means for securing said units together, a transversely extending operating device common to all said units, and means for synchronizing the movement of both ends of said device, substantially as set forth.

60 9. A calculating machine for calculating in a plurality of numerical orders comprising a plurality of individual units each having a support, and a row of keys, key-actuated devices, calculating mechanism controlled by said devices and carrying mecha-

nism all mounted on said support, and means for securing said units together, substantially as set forth.

10. A calculating machine for calculating in a plurality of numerical orders comprising 70 a plurality of individual units each having a support, and a row of keys, a device movable under the control of the keys in one direction, calculating mechanism connected to said device, and carrying mechanism all mounted on said support, means for securing said units together, and an operating member common to all said units and adapted to move the said devices thereof in the opposite direction, substantially as set forth. 80

11. A calculating machine for calculating in a plurality of numerical orders comprising a plurality of individual units each having mechanism for calculating in one numerical order and carrying mechanism, 85 means for securing said units together, a number-wheel shaft extending transverse to said units, and a plurality of number-wheels on said shaft one for each unit and each actuated by the calculating mechanism of the 90 corresponding unit, substantially as set forth.

12. A calculating machine for calculating in a plurality of numerical orders comprising a plurality of individual units each having mechanism for calculating in one numerical order and carrying mechanism, means for securing said units together, a number-wheel shaft extending transverse to said units, a plurality of number-wheels on 100 said shaft one for each unit and each actuated by the calculating mechanism of the corresponding unit, and means for actuating said number-wheels to turn them all simultaneously to the zero position, substantially 105 as set forth.

13. A unit for use in a calculating machine comprising a support, a row of keys thereon, a movable device mounted on said support and movable in one direction when 110 a key is depressed a distance corresponding to the value of the key depressed, a wheel mounted on said support rotated when returning said device to its initial position and carrying mechanism also mounted on said 115 support, substantially as set forth.

14. A unit for use in a calculating machine comprising a support, a row of keys thereon, a movable device mounted on said support and movable in one direction when 120 a key is depressed a distance corresponding to the value of the key depressed, means on said support for locking the key depressed in its depressed position and the other keys in the row against depression, a wheel mounted on said support rotated when returning said device to its initial position, and carrying mechanism also mounted on said support, substantially as set forth. 125

15. A unit for use in a calculating ma- 130

chine comprising a support, a row of keys thereon, a movable device mounted on said support and movable in one direction when a key is depressed a distance corresponding to the value of the key depressed, a wheel pivotally mounted on said support, a pawl pivotally mounted concentric with said wheel and connected to said device, and carrying mechanism also mounted on said support, substantially as set forth.

16. A calculating machine for calculating in a plurality of numerical orders comprising a plurality of individual units each having mechanism for calculating in one numerical order and carrying mechanism including a laterally projecting member, means for spacing said units apart, means for securing the units together side by side with the laterally projecting member of the carrying mechanism of each unit in position to engage the mechanism of the next adjacent unit, an operating device common to all the units, and means for operating the same, substantially as set forth.

25. 17. A calculating machine for calculating in a plurality of numerical orders comprising a plurality of individual units each having a support, a row of keys mounted thereon, a bar slideable upon the support under the control of the keys, a wheel pivotally mounted on the support, a pawl pivotally mounted on the support concentric with said wheel and connected to said slide bar and carrying mechanism also mounted on said support, and means for securing said units together, substantially as set forth.

18. A calculating machine for calculating in a plurality of numerical orders comprising a plurality of individual units arranged side by side and each having mechanism for calculating in one numerical order and carrying devices for engaging and operating the calculating mechanism of the next adjacent unit, and means for securing the plurality of individual units together, substantially as set forth.

25. 19. A calculating machine for calculating in a plurality of numerical orders comprising a plurality of individual units arranged side by side and each having a support and calculating mechanism for one numerical order, carrying mechanism and spacers on said supports, means for securing said units together and plates at opposite sides of the plurality of units spaced therefrom but secured thereto, substantially as set forth.

20. In a calculating machine, the combination of a row of keys, a pivoted sliding bar adapted to be engaged and rocked by any one of said keys, a spring for rocking said bar in the direction opposite to that in which it is turned by the keys, and a stud on said support in position to engage the end of said bar when the latter is turned by said spring, said bar being adapted to en-

gage said support at the base of said stud, substantially as set forth.

21. In a calculating machine, a support, a row of keys mounted for movement thereon, a bar movable under the control of said keys, a projection on each key, a multiplying strip having projections thereon to engage said projections on the keys, parallel links pivotally connected to said support and said strip, and means for actuating said strips, substantially as set forth.

22. In a calculating machine, the combination of a row of keys, a sliding bar controlled thereby, a rotatable gear wheel, a pawl coacting therewith pivotally mounted concentric with said wheel and connected to said bar, an error lever also pivotally mounted concentric with said gear and provided with gear teeth, and a slidable error key provided with rack-teeth engaging the gear teeth on said lever and adapted to operate the lever to cause it to engage said pawl and restore it to normal position, substantially as set forth.

23. In a calculating machine, the combination of a toothed wheel mounted for rotation, an arm pivotally mounted concentric with said wheel, a pawl mounted on said arm and coacting with said wheel, key-actuated devices for positioning said arm, means for operating said arm, and means carried by said arm for giving said pawl an extra movement to carry over from one denomination to another, substantially as set forth.

24. In a calculating machine, the combination of a toothed wheel mounted for rotation, an arm pivotally mounted concentric with said wheel, a pawl mounted on said arm and coacting with said wheel, key-actuated devices for positioning said arm, means for operating said arm, means carried by said arm for giving said pawl an extra movement to carry over from one denomination to another, and spring-actuated devices for operating said means, substantially as set forth.

25. In a calculating machine, the combination of a toothed wheel mounted for rotation, an arm pivotally mounted concentric with said wheel, a pawl mounted on said arm and coacting with said wheel, key-actuated devices for positioning said arm, means for operating said arm, means carried by said arm for giving said pawl an extra movement to carry over from one denomination to another, a detent controlling the operation of said means, and means for operating said detent, substantially as set forth.

26. In a calculating machine, the combination of a toothed wheel mounted for rotation, an arm pivotally mounted concentric with said wheel, key-actuated devices for positioning said arm, means for operating said arm, a lever pivotally mounted on said arm, and a pawl pivotally mounted on said

lever and engaging the teeth of said wheel, substantially as set forth.

27. In a calculating machine, the combination of a toothed wheel mounted for rotation, an arm pivotally mounted concentric with said wheel, key-actuated devices for positioning said arm, means for operating said arm, a lever pivotally mounted on said arm, a pawl pivotally mounted on said lever and engaging the teeth of said wheel, means for turning said lever on its pivot, a latch for said lever and means for operating said latch, substantially as set forth.

28. In a calculating machine, the combination of a toothed wheel mounted for rotation, an arm pivotally mounted concentric with said wheel, key-actuated devices for positioning said arm, means for operating said arm, a lever pivotally mounted on said arm, a pawl pivotally mounted on said lever and engaging the teeth of said wheel, spring-actuated devices brought into coaction with said lever when said arm is operated by said operating means, a detent for said lever, and means for operating said detent, substantially as set forth.

29. In a calculating machine, the combination of a toothed wheel mounted for rotation, a pawl mounted for movement concentric with said wheel and adapted to engage the teeth thereof, a pivoted lever adapted to actuate said pawl to cause it to make an extra movement to carry over from one denomination to another, and means for locking said lever against movement, substantially as set forth.

30. In a calculating machine, the combination of a toothed wheel mounted for rotation, a pawl mounted for movement concentric with said wheel and adapted to engage the teeth thereof, a pivoted lever adapted to actuate said pawl to cause it to make an extra movement to carry over from one denomination to another, spring-actuated devices brought into coaction with said lever to operate the same, and means for locking said lever against movement, substantially as set forth.

31. In a calculating machine, the combination of a toothed wheel mounted for rotation, a pawl mounted for movement concentric with said wheel and adapted to engage the teeth thereof, a pivoted lever adapted to actuate said pawl to cause it to make an extra movement to carry over from one denomination to another, spring-actuated devices brought into coaction with said lever to operate the same, a latch for said lever, means for releasing said latch and means for locking said lever against movement, substantially as set forth.

32. In a calculating machine, the combination of a toothed wheel mounted for rotation, a pawl mounted for movement concentric with said wheel and adapted to engage the teeth thereof, a pivoted lever adapted to actuate said pawl to cause it to make an extra movement to carry over from one denomination to another, key-actuated devices for positioning said arm, means for operating said arm, a lever pivotally mounted on said arm, a pawl pivotally mounted on said lever and engaging the teeth of said wheel, an operating device for moving said pawl and wheel, a pivoted lever adapted to actuate said pawl to cause it to make an extra movement to carry over from one denomination to another, a lock for holding said lever against movement adapted to be released by said operating device, substantially as set forth.

33. In a calculating machine, the combination of a toothed wheel mounted for rotation, a pawl mounted for movement concentric with said wheel and adapted to engage the teeth thereof, key-actuated devices, an operating device for moving said pawl and wheel, a pivoted lever adapted to actuate said pawl to cause it to make an extra movement to carry over from one denomination to another, and a lock for holding said lever against movement adapted to be released by said operating device, substantially as set forth.

34. In a calculating machine, the combination of a toothed wheel mounted for rotation, an arm pivotally mounted concentric with said wheel, key-actuated devices for positioning said arm, means for operating said arm, a lever pivotally mounted on said arm, a pawl pivotally mounted on said lever and engaging the teeth of said wheel, and a lock for said lever actuated to release the lever by said operating means, substantially as set forth.

35. In a calculating machine, the combination of a toothed wheel mounted for rotation, an arm pivotally mounted concentric with said wheel, key-actuated devices for positioning said arm, means for operating said arm, a lever pivotally mounted on said arm, a pawl pivotally mounted on said lever and engaging the teeth of said wheel, a lock for said lever actuated by said operating means, spring-actuated devices brought into coaction with said lever when said arm is operated by said operating means, a latch for said lever, and means for releasing said latch, substantially as set forth.

36. In a calculating machine, the combination of a plurality of toothed wheels arranged parallel one to another, a pawl for each wheel, an operating device extending transverse to said wheels for operating all of said pawls, and means eccentric to said wheels for causing both ends of said operating device to move in unison, substantially as set forth.

37. In a calculating machine, the combination of a plurality of toothed wheels arranged parallel one to another, a pawl for each wheel, an operating device extending transverse to said wheels for operating all

of said pawls, and gearing eccentric to said wheels between the ends of said operating device, substantially as set forth.

38. In a calculating machine, the combination of a plurality of toothed wheels arranged parallel one to another, a pawl for each wheel, key-actuated devices for positioning said pawls, a rod extending transversely to said wheels and adapted to operate said pawls, and gearing exterior to said wheels between the ends of said rod, substantially as set forth.

39. In a calculating machine, the combination of a plurality of toothed wheels arranged parallel one to another, a pawl for each wheel, key-actuated devices for positioning said pawls, a rod extending transversely to said wheels, pivotally mounted supports for said rod concentric with said wheels, and gearing between said supports for causing them to move in unison, substantially as set forth.

40. In a calculating machine, the combination of a plurality of toothed wheels arranged parallel one to another, a pawl for each wheel, key-actuated devices for positioning said pawls, a rod extending transversely to said wheels, pivotally mounted supports for said rod concentric with said wheels, a rotatable shaft parallel to said rod, and gears on said shaft meshing with teeth formed in said supports, substantially as set forth.

41. In a calculating machine, the combination of an operating arm, means for actuating the same, a carrying lever movably mounted on said arm, means for subjecting said carrying lever to spring pressure when said lever and arm are moved by said actuating means, and means operated by said actuating means for relieving said lever of pressure, substantially as set forth.

42. In a calculating machine, the combination of an operating arm, a carrying lever movably mounted thereon, a reciprocatory operating device for moving said arm and lever in one direction and then returning it to initial position, means for subject-

ing the carrying lever to spring-tension when the same is actuated by the movement of said operating device in one direction, and means actuated by said operating device when moving in the opposite direction for relieving said spring tension, substantially as set forth.

43. In a calculating machine, the combination of a rotatable toothed wheel, an arm movable concentric therewith, a carrying lever pivotally mounted on said arm, a pawl engaging said wheel and adapted to be actuated by said lever to make an extra movement to carry over from one denomination to another, means for moving said arm and lever, a spring-actuated lever engaged by said carrying lever when the latter is moved by said means, and means for actuating said last-named lever to relieve the tension thereof on said carrying lever, substantially as set forth.

44. In a calculating machine, the combination of a plurality of wheels, key-set devices for controlling the position thereof, an operating device for operating said wheels, carrying mechanism for operating the wheels to carry from one denomination to another, and a lock for the carrying mechanism actuated to release said mechanism by said operating device, substantially as set forth.

45. In a calculating machine, the combination of a toothed wheel mounted for rotation, an operating arm pivoted concentric therewith, a pawl carried by said arm, means for actuating said arm to cause the pawl to actuate the wheel, a permanent stop to arrest rotation of said arm and prevent overthrow thereof, and means for moving the pawl independently of the arm to carry from a lower to a higher denomination, substantially as set forth.

This specification signed and witnessed this 10th day of August, 1910.
